Design No. 12,084, dated January 4, 1881.

SONNET.

UNITED STATES PATENT OFFICE.

HENRY J. DAVIES, OF BROOKLYN, NEW YORK.

DESIGN FOR A CLOCK-STAND.

SPECIFICATION forming part of Design No. 12,084, dated January 4, 1881.

Application filed September 14, 1880. Term of patent 7 years.

To all whom it may concern:

Be it known that I, HENRY J. DAVIES, of Brooklyn, in the county of Kings and State of New York, have originated and produced a certain new and Improved Design for a Clock-
Stand, of which the following is a specification.

My design is applicable to those clocks in which are comprised a rotating dial and a stationary hand or pointer.

The character of my design is clearly shown in the accompanying drawing, which represents a face view of a clock-stand embodying said design.

The general form of the clock-stand is that of a banner suspended from a standard, the standard being represented as behind the banner.

The standard A is composed of a broad circular base portion, a, curving inwardly to form a slender stem or shaft, b, covered with leaf or foliated ornamentation. At the top of the standard is a battle-ax, c, and from a point just below the battle-ax two chains, S, extend outwardly and are attached to the upper bar or rod, C, of the banner B. The ends of both the upper and lower bars or rods, C D, have conical terminals e, and from the ends of the upper bar or rod depend cords and 30 tassels f. Above the bar or rod C is an arched center, E, the main portion of which consists of a sunken panel bearing scrolled ornaments in relief. Below the bar or rod D are projections F, of curved outline, which comprise 35 sunken panels bearing scrolled or foliated ornamentations in relief, and from each projection depends a tassel, g.

The body portion of the banner B is com-

posed of black velvet or other material, furnishing a proper ground, secured to a board 40 or base in which is an opening, h, through which the dial is visible, and from which an index-finger or pointer, i, extends. Upon the black or other ground, in silvered bass-relief, are secured song-birds j, perched upon a 45 bough, k, bearing leaves and flowers, and over these is secured a glass plate, held in place by a surrounding bezel, l.

The border m of the banner is ornamented upon the face by a representation of a running vine.

What I claim as new, and desire to secure by Letters Patent, is—

1. A design for a clock-stand, consisting of the circular base portion a, the stem or shaft 55 b, the battle-ax c, the chains s, and the banner B, as described and shown.

2. A design for a clock-stand, consisting of the standard A, the banner B, having an opening through which the dial is visible, and the 60 song-birds j, as described and shown.

3. A design for a clock-stand, consisting of the circular base portion a, the stem or shaft b, the battle-ax c, the chains s, and the banner B, comprising the rods or bars C D, the 65 arched center E, the projections F, and the song-birds j and bough k, as described and shown.

4. The design for the ornamentation for the front of a clock-stand, consisting of the song- 70 birds j and the bough k, as described and shown.

HENRY J. DAVIES.
